UNITED STATES PATENT OFFICE.

WILLIAM CLEGG, OF TORONTO, ONTARIO, CANADA, ASSIGNOR TO INTERNATIONAL MACHINERY & SUPPLY CO. LIMITED, OF MONTREAL, QUEBEC, CANADA.

PISTON-ROD MOISTURE SWAB.

Application filed May 19, 1921. Serial No. 471,024.

To all whom it may concern:

Be it known that I, WILLIAM CLEGG, a subject of the King of Great Britain, and residing at 72 Waverley Road, of the city of Toronto, in the Province of Ontario, in the Dominion of Canada, have invented a new and useful Piston-Rod Moisture Swab, of which the following is the specification.

The invention relates to piston rod moisture swab as described in the present specification and illustrated in the accompanying drawings, that form part of the same.

The invention consists essentially of the novel construction pointed out broadly and specifically in the claims for novelty following a description in detail of the preferred form of the device.

The objects of the invention are to eliminate the leak of water along a piston rod into a machine operated by a steam motor thereabove; to particularly overcome the inconveniences and difficulties in air pumps incident to the entrance of water into the compressor chamber from the steam chamber thereabove, such as is experienced in the air compressor on locomotives; to effect these purposes in a simple and inexpensive manner; and generally to provide an attachment, which is cheap, durable and efficient in avoiding the water troubles in air pumps.

In the drawings, Figure 1 is an outline of a portion of the locomotive, showing the steam operated air compressor and the invention applied thereto.

Figure 2 is an enlarged sectional view of the stuffing boxes and the swab therebetween, showing the piston rod extending therethrough.

Figure 3 is a cross sectional view on the line 3—3 in Figure 2.

Figure 4 is a perspective detail of the swab casing apart from the piston rod.

Like numerals of reference indicate corresponding parts in each figure.

Referring to the drawings, the invention is shown between the engine 1 and compressor 2 of an air pump of a locomotive and encircles the piston rod 3.

The upper and lower stuffing boxes 4 and 5 respectively are externally threaded and closed in by the caps 6 and 7 which press the gaskets 8 and 9 toward the springs 10 and 11, said caps having the spanner bosses 12 and 13.

The two halves 15 and 16 of the swab casing 14 are joined by the barrel hinge joints 17, said hinge joints having cotter pins 18, and each said half of swab casing having discharge ports 19 at the lower end thereof, and the half 16 having an oil inlet adapted to be connected to a suitable lubricating oil supply by the pipe 20. From the inner walls of the said halves 15 and 16 the flanges 22 and 23 extend inwardly and terminate before they reach the piston rod 3, so that there is an annular port for the discharge of condensation water around the said piston rod 3, and at the same time the said flanges act as a support for the swab 24, which encircles the piston rod 3 between the halves 15 and 16, forming the said casing 14, and completely filling the space between said casing 14 and said piston rod 3. The extreme ends of the walls of said casing 14 project over the nuts 6 and 7 and come into contact with the spanner bosses 12 and 13 and form a spacer therebetween. An absolute lock for the nuts 6 and 7 is consequently formed as the said nuts cannot move so long as they are spaced in this manner.

In the operation of this invention the condensation water leaking down on the periphery of the piston rod 3 eventually finds its way through the stuffing box 4, no matter how careful the packing may be arranged. But when this condensation water enters the swab casing 14 it is wiped by the swab 24, and the rod is completely cleared of all moisture, the surplus water flowing through the port surrounding the piston rod at the flanges 22 and 23 and through the discharge ports 19. The said discharge ports are left open so that water may flow harmlessly away from the rod. In this way no water reaches the compressor chamber. The piston rod is wiped with an oily swab, which affords excellent lubrication as this oil is an additional protection against the entrance of water into the compressor chamber.

What I claim is:

1. In a piston rod moisture swab device, a piston rod, a swab casing having inwardly extending projections spaced from the lower end and having openings in the wall below said projections encircling the piston rod, an air pump having a steam mechanism, driving a compressor mechanism, and the

piston rod forming the connection therebetween, and a swab in the casing supported by the projections and encircling said piston-rod between said steam-mechanism and said compressor mechanism.

2. In a piston rod moisture swab, a piston rod extending between an air pump and its drive member mounted on said pump and said drive member respectively, a pair of 10 stuffing boxes closed in at the end by caps, a swab encircling the piston rod and a swab casing in vertical halves suitably joined and having flanged sections supporting said swab, and water discharge ports beneath 15 the flanges.

3. In a piston rod moisture swab, a piston rod extending between an air pump and its drive member mounted on said pump and said drive member respectively, a pair 20 of stuffing boxes closed in at the end by caps, a swab encircling said piston rod between said stuffing boxes and a swab casing formed in halves, each half having a flanged section towards its lower end and 25 ports beneath the flanged sections, and one of said halves having an oil inlet adapted

to be connected to a suitable lubricant supply.

4. In a piston rod moisture swab, a piston rod extending between an air pump and its 30 drive member mounted on said pump and said drive member respectively, a pair of stuffing boxes, each stuffing box having the packing therein enclosed by screw caps, said screw caps having vertical spanner bosses 35 therearound, a swab of suitable material encircling said piston rod between said caps and a swab casing formed in halves and extending over said caps into contact with said spanner bosses and joined by barrel 40 hinged joints and pins, each of said halves having flanges extending part way to said piston rod and supporting said swab as well as water discharge ports below said flanges, and one of said halves having an oil inlet 45 adapted to be connected to a suitable supply.

Signed at Toronto, Ont., this 13th day of May, 1921.

WILLIAM CLEGG.
